Filed July 6, 1959, Ser. No. 825,220

Claims priority, application Belgium July 10, 1958
7 Claims. (Cl. 214—310)

The invention relates to a mechanism for extracting a document out of a document carrier and particularly when this document is in a document carrier of the kind described in our Belgian Patent No. 544,840.

A mechanism accomplishing this operation is already known from our Belgian Patent No. 577,768. In this mechanism the document carrier is first opened by a mechanism provided with a pneumatic device and then another mechanism also provided with a pneumatic device is introduced in the document carrier to extract the document therefrom. This overall mechanism is rather complicated and necessitates the application of a partial vacuum to the various pneumatic devices.

An object of the present invention is to realize the extraction of the document without the help of pneumatic devices and by relatively simple means.

Another object of the invention is to suppress the opening mechanism of the document carrier.

According to a characteristic of the invention, the extraction of said document is operated without opening the document carrier, by the action of wheels with adherent rims acting on said document through holes made in the document carrier.

According to another characteristic of the invention, said extracting system by wheels is surmounted by a belt conveyor seizing the document as soon as it emerges from the document carrier completing the extraction of the document and depositing it in an adjacent device.

The objects and characteristics of the invention described above as well as others and the way of attaining them will become more apparent and the invention itself will be best understood by referring to the following description of an embodiment of the invention taken in conjunction with the accompanying drawings in which:

FIG. 1 represents a schematic perspective view of the whole of the mechanism which will be described later.

FIG. 2 is a schematic side view of this mechanism.

In the preferred embodiment of a mechanism according to the invention, the document carrier 1 is taken along grooves 2 and 2' by means which may for instance be those cited in our Belgian Patent No. 568,795, until the place where it is represented on FIG. 1 and where the extraction of the document is made. On this travel, groove 2 produces at 3 a slight deviation of the upper edge of the higher flap of the document carrier without however causing a complete opening of the document carrier. This slight deviation has as its objective to prevent, upon rising, the upper edge of the document from catching into the folded part of said upper edge of the higher flap of the document carrier.

During the displacement of the document-carrier in the grooves 2 and 2' its lower part is guided by parallel straight rods 4, 4', 5 and 5' the exact purpose of which will be explained further.

The document-carrier used in the present mechanism is perforated with a certain number of holes such as 6 which can be located on one or more horizontal rows and can be staggered as shown or superposed, and whose number and whose distances between one another are chosen in function of the dimensional limits of the documents to be processed.

When the document-carrier is stopped at its extracting

2

place (FIG. 1) the upper edge of its higher flap is maintained separated from the plane of the document-carrier by the plane surface obtained behind the curved front part 7 of part 8 (this plane surface being in the prolongation 5 of groove 2 beyond deviation 3).

The extraction of the document is now performed by the action of an assembly of small rubber wheels such as 9 fixed on shafts 10 and 11 mounted in free rotation between the upper branches 12 and 12' of two levers 13 and 13'. These levers 13 and 13' are fixed on a shaft 14 which can pivot in bearings (not shown) fixed on the frame (not represented) of the mechanism. The upper ends of branches 12 and 12' are kept at a fixed distance by a rod 15; in the same way, the lower ends of levers 13 and 13' are kept at a distance by rod 16.

An assembly of rubber wheels and levers similar to assembly 9, 10, 11, 12, 12', 13, 13' is arranged at the other side of the document carrier respectively in 17, 18, 19, 20, 20', 21 and 21' (FIG. 2) with this difference that axes 18 and 19 are permanently rotated under the action 20 of driving means identified by M. This driving means M drives shaft 22 in the sense of arrow 23, and at the same time pulley 24 integral therewith and on which passes belt 25. This belt actuates pulley 26 which is integral with pulley 27; pulleys 26 and 27 can rotate freely on an end of the rotating shaft 28 of levers 21 and 21'. At the end of shafts 18 and 19 pulleys 29 and 30 are fixed, and a belt 31 transmits the movement of pulley 27 to the latter pulleys. An idler pulley 32 forces belt 31 to surround sufficiently pulley 30 and acts at the same time as belt tensioner.

The pivoting of levers 13 and 13' is controlled by a solenoid 33 which, when it is energised, attracts its connecting rod 34 and at the same time the lower end of levers 13 and 13' by means of rod 16. A similar pivoting movement is transmitted to levers 21 and 21' due to the fact that the ends of rod 16 which protrude beyond levers 13 and 13' glide in oblique buttonholes 35 and 35' made in the lower ends of levers 21 and 21'. As levers 13 and 13' pivot about shaft 14 in a direction to move wheels 9 into holes 6, rods 16 produce a downward force on buttonholes 35 and 35' causing levers 21 and 21' to pivot about shaft 28 thereby also moving wheels 17 into operating position.

Above part 8 is arranged a wide belt 36 supported by two rollers 37 and 38 the lower course of which matches over a certain length curve 7 of part 8, and slides on the upper plane of this part. Shaft 39 of roller 38 is put into rotation from driving means M by means of pulley 40, belt 41, pulley 42, shaft 43 and gear 44. It is to be noted that the different movement transmissions of the driving means M are so adjusted that the linear velocity of belt 36 is equal to the velocity of the rim of wheel 9.

To extract the document, solenoid 33 is energised by 55 electrical circuits associated with the mechanism and under this action wheels 9 and 17 will press the document through holes 6, and by their rotation movement, make the document rise until its upper edge is engaged between the curved part 7 and the lower part of belt 36. The latter 50 cooperates with the assembly of wheels 9 and 17 to complete the extraction of the document, and afterwards only belt 36 carries away the document along the plane of part 8 until it is ejected according to arrow 45 towards any appropriate device.

The object of rods 4, 4', 5 and 5' is to take care that 65 at the level of the holes 6, the two flaps of the document carrier are not separated so that wheels 9 and 17 do not enter into contact with the edges of holes 6.

During this extracting operation the upper edge 46 of the higher flap of the document carrier is kept in place 70 by a pusher 47 fixed to one end of two resilient branches 48 and 48' the other end of which is fixed to the upper

part of branches 20 and 20'. When the mechanism is at rest pusher 47 is of course separated from the trajectory of the edge 46 of the document carrier and its pressure action only takes place at the moment branches 20 and 20' are displaced towards the document carrier under the action of solenoid 33.

It is to be noted that the slight deviation of the upper edge of the document carrier in order to prevent that the document would meet the inner over-thickness is not absolutely essential, and that it is sufficient to keep this upper edge in place while the trajectory of the document is deviated, by curving the document carrier by a suitable action of the extracting or auxiliary wheels.

While the principles of the invention have been described above in connection with specific apparatus, it is to be clearly understood that this description is made only by way of example and not as a limitation on the scope of the invention.

We claim:

1. A mechanism for extracting a document from a document carrier which has at least one open edge and having openings extending through the sidewalls thereof and including a device to position said document carrier within said mechanism, comprising a pair of laterally movable elements located on opposite sides of said document carrier, a plurality of wheels rotatably mounted on each of said movable elements and positioned thereon adjacent holes through the sidewalls of said document carrier, means for rotatably driving said plurality of wheels on at least one movable element, means for laterally moving said movable elements towards the document carrier to cause said wheels to extend into the holes and produce a sliding of the document toward an open edge of said document carrier, and means for further conveying said document as it emerges from an open edge of said document carrier.

2. A mechanism as claimed in claim 1 wherein said wheels on one movable element are located thereon symmetrically with respect to said wheels of the said movable

element on the other side of said document carrier so that the wheels face each other through the holes in the sidewalls of said document carrier.

3. A mechanism as claimed in claim 1 further comprising a deviating portion on said positioning device for slightly deviating the edge of a sidewall of the document carrier where an inward protruding thickness exists, so that it is no longer in the path of the document when it is being extracted.

10 4. A mechanism as claimed in claim 1 wherein said document carrier is curved by the pressure of said wheels so that the inward protruding thickness of the edge of a sidewall of said document carrier is no longer in the path of the document as it is being extracted.

15 5. A mechanism as claimed in claim 1 further comprising a pusher for holding an edge of a sidewall firmly in place when said movable members have been laterally moved towards said document carrier.

6. A mechanism as claimed in claim 1 wherein said 20 means for further conveying said document as it emerges from an open edge of said document carrier comprises a belt conveyor.

7. A mechanism as claimed in claim 3 wherein said 25 positioning device comprises a grooved member for guiding the upper edges of the two sidewalls of said document carrier, said grooved member being slightly deviated laterally and reduced in height near the end adjacent the operating position so that the higher side wall only is deviated.
